UNITED STATES PATENT OFFICE.

WILLIAM I. WHEELER AND JOHN J. BULL, OF SCOTTSVILLE, ILLINOIS.

EXPANSIBLE AUGER.

SPECIFICATION forming part of Letters Patent No. 732,479, dated June 30, 1903.

Application filed March 14, 1903. Serial No. 147,797. (No model.)

To all whom it may concern:

Be it known that we, WILLIAM I. WHEELER and JOHN J. BULL, citizens of the United States, residing at Scottsville, in the county 5 of Macoupin and State of Illinois, have invented certain new and useful Improvements in Expansible Augers, of which the following is a specification.

This invention relates to improvements in 10 expansible augers; and its object is to provide an auger which is divided into a stationary and movable portion, the latter comprising a pair of hinged members adapted to be oppositely moved on each other to increase 15 the diameter of a bore.

A further object of the invention is to provide the hinged members with guides which receive a stem and lock said members in position. Said stem when moved rocks the 20 hinged members and increases the size of the auger.

Many other objects and advantages will be hereinafter referred to and be particularly pointed out in the claims.

25 In the drawings, Figure 1 is a side elevation of the invention. Fig. 2 is a similar view, the diameter of the auger having been increased. Fig. 3 is a view at right angles to Fig. 1. Fig. 4 is a view similar to Fig. 1, one 30 of the hinged members being removed. Fig. 5 is a sectional view on the line X X of Fig. 1. Fig. 6 is a cross-section on the line Y Y of Fig. 1. Fig. 7 is a similar view on the line Z Z of Fig. 1. Fig. 8 is a similar view on the line 35 W W of Fig. 1. Fig. 9 is a detail perspective view of the movable members. Fig. 10 is an enlarged detail perspective view of the stem.

The numeral 1 represents an auger comprising 40 a stem 2, a stationary portion 3, and movable or expansible portion 4. The portion 3 is tubular, as at 4^a, and has depending from its lower edge a pair of ears 5, provided with trunnions 6, the bottom edge between 45 the ears being rounded off, as at 7. 8 indicates a pair of inwardly-projecting lugs at the lower inner edge of the tube 4^a, and they serve to guide the stem 2 when the parts are assembled. The portion 4 consists of two members 50 9 and 10, each being exactly alike; but when placed side by side their grooves and guides, now to be described, are disposed on

opposite sides of a medial line. Each member is hollow, as at 11, and has a flat wearing-surface 12, which is cut away at 13 to receive 55 the stem. At the bottom of the cut-away portion 13 and forming a continuation thereof is an inclined slot 14, which is narrower than the cut-away portion and inclines from the outer wall of the portion 11 toward the center 60 of the auger. The upper edge 11^a of the hollow portion is inwardly rounded to fit the rounded lower edge 7 of stationary portion 3. A perforated ear 15 projects upwardly from the edge 11^a and is in alinement with the 65 trunnions 6. 16 indicates the threads of the members 9 and 10, and when placed side by side they register and form a continuation of the threads 17 of the portion 3. Two threads are shown on the portion 4, which terminate 70 in a cutting edge 18, while but a single thread is shown on the portion 3. This, however, may be varied.

The operating-stem is an important element in this invention, and it will now be described in detail. The lower part of the stem is slotted, as at 20, forming two legs 21 21, connected at their extreme lower end by a rounded connecting-bar 22, the edges 23 of the legs 21 opposite the bar 22 being widened 80 out to form overhanging flanges 24. Each leg widens out, as indicated at 25, to provide overhanging flanges 26 to engage the lugs 8 to prevent the stem from turning in the stationary portion 3. It will be observed that 85 the flanges 26 are disposed on opposite sides of the center of the stem and are continuation of the legs 21, this being for the purpose of allowing the members 9 and 10 to rock freely on their hinges to avoid interlocking of the 90 parts. A shoulder 28 on the stem limits its upward movement against a collar 29, threaded in the upper end of the portion 3. This insures the movement of the members 9 and 10 being limited and prevents the connecting-bar 22 becoming disengaged from the 95 slots 14. A hand-nut 30 engages the upper threaded end of the stem to rock the members 9 and 10 on their hinges. When the parts are assembled, the stem is guided by the lugs 100 8 and is thus prevented from rotating, the flanges 26 fitting under the edges of the flat surfaces 12, adjacent the cut-out portions 13, while the connecting-bar 22 engages the in-

clined slots 14. When the members 9 and 10 are in their normal position, the slots 14 form a V, as shown in dotted lines in Fig. 1, the connecting-bar 22 engaging them at the apex, 5 so that any movement imparted to the stem will cause the bar 22 to ride in said slots 14 and rock the members 9 and 10.

In operation the auger is driven to work in any well-known manner, and after it has been 10 driven in the required depth and just before stopping its inward feed and it is found desirable to enlarge the diameter of the bore within the surface the hand-nut 30 is turned gradually, and as the stem cannot revolve it 15 follows that said stem will be drawn up within the auger. Such movement causes the bar to impinge the walls of the slots 14 in the members 9 and 10, which spreads the latter outwardly, as shown clearly in Fig. 2. This 20 action, of course, turns the members on their hinges, a smooth joint between the members and the stationary portion 3 being maintained by rounding the edges 7 and 11^a, forming somewhat of a ball-joint, and thus making 25 the interior of the bore of conical formation.

The stem is limited in its movement by the shoulder 29, which is placed relative to the sleeve, so that its movement will just be equal to the length of the slots 14, and the 30 members 9 and 10 are prevented from becoming displaced from their hinge connections by the flanges 24 of the legs 21 21 engaging the edges of the slots 14 and the flanges 26 engaging the under side of the surfaces 12. 35

In forming a straight hole the members 9 and 10 are held in alinement and braced against each other by one of the edges of the surface 12 engaging the terminal of the 40 thread of the companion member, as indicated at 31.

Our invention, it is thought, will be fully understood and appreciated by those skilled in the art to which it appertains. While it 45 is primarily designed for use in drilling holes where blasting is to be done—for instance, in rock-drilling or coal-mining—its use is not at all limited to this field of usefulness, and it is equally valuable in other classes of work.

50 We are aware it is old in the art to provide an expandible auger, and do not claim such broadly; but, believing it to be new with us to hinge two members of an auger to rock on each other and being operated by a reciprocated stem,

55 What we claim as new is—

1. An expandible auger comprising a stationary portion, a movable portion composed of two independently-hinged members adapted to work on and against each other in opposite directions, and means for rocking the hinged members, substantially as described.

2. An expandible auger comprising a stationary portion, a movable portion composed of two independently-hinged members adapted to work on and against each other, a slot 65 being formed in each member, said slots be-

ing inclined in opposite directions with respect to each other, and a stem engaging the slots, said stem adapted to be reciprocated to rock the members on their hinges to increase the diameter of the auger, substantially as described.

3. An expandible auger comprising a stationary portion, a movable portion composed of two independently-hinged members adapted to work on and against each other in opposite directions, means for rocking the hinged members to increase the diameter of the auger, and flanges on the hinged members, said flanges coacting with the means for rocking the hinged members to fasten said members to the stationary portion, substantially as described.

4. An expandible auger comprising a stationary portion, a movable portion composed of two independently-hinged members adapted to work on and against each other in opposite directions, a stem working within the two portions of the auger, means for preventing the stem revolving within the two portions, and means on the hinged members which coact with the stem to fasten the said members to the stationary portion, substantially as described.

5. An expandible auger comprising a stationary portion which is rounded at its lowest edge, a movable portion composed of two independently-hinged members adapted to work on and against each other, the upper edges of the members being internally rounded to receive and fit the rounded edge of the stationary portion, and a stem for rocking the members on their hinges in opposite directions, substantially as described.

6. An expandible auger comprising a stationary portion which is hollow, lugs within the stationary portion, a movable portion composed of two members hinged to the stationary portion, a stem, said stem being prevented from rotating by the lugs, means on the members which is engaged by the stem for rocking the members on their hinges, and means for actuating the stem, substantially as described.

7. An expandible auger comprising a stationary portion, a movable portion composed of two members which are hollow, each having flanges and being hinged to the stationary portion, and a reciprocating stem having flanges which coact with the flanges on the members, said stem also engaging the members to rock them on their hinges, substantially as described.

8. An expandible auger comprising a stationary portion, a movable portion composed of two members which are hollow and have slots inclining in opposite directions, and means for fastening the stationary portion, the movable portion and the stem together, said stem having a bar which engages the slots to oppositely rock the members when the stem is reciprocated, substantially as described.

9. An expandible auger comprising a stationary portion, a movable portion composed of two members which are hinged to the stationary portion, said members having slots, and means coacting with the slots for rocking the members in opposite directions, substantially as described.
10. An expandible auger comprising a stationary portion having a spiral thread, a movable portion having a double thread and composed of two hinged members, one of the threads of the movable portion registering

with the thread of the stationary portion, and means for rocking the members to engage the movable end of the auger, substantially as 15 described.

In testimony whereof we have signed our names to this specification in presence of two witnesses.
